ATTORNEYS

UNITED STATES PATENT OFFICE.

EDWARD E. LAMICA, OF CHESTER, SOUTH CAROLINA.

CURTAIN CARRIER.

Application filed June 29, 1922. Serial No. 571,693.

To all whom it may concern:

Be it known that I, EDWARD E. LAMICA, a citizen of the United States, and resident of Chester, in the county of Chester and State 5 of South Carolina, have invented certain new and useful Improvements in Curtain Carriers, of which the following is a specification.

My invention relates to curtain carriers 10 for vehicles provided with tops, and it consists in the combinations, constructions and arrangements herein described and claimed.

As is well known, tops for automobiles and like vehicles ordinarily include side curtains 15 detachably secured at their upper ends to longitudinal bows or associated frame members of the body and detachably secured at their lower ends to the doors of the automobile at the upper ends of the latter. In 20 stormy and rainy weather, it is ordinarily necessary to detach the side curtains from the doors when the doors are opened and to again secure the curtains to the doors when the latter are closed. In consequence, con- 25 siderable inconvenience, labor and annoyance are occasioned by the necessity of repeatedly detaching and attaching the side curtains to the doors of the vehicles under unfavorable weather conditions. Moreover, 30 the curtains are likely to be torn and rendered unserviceable or insightly because of the wear thereon resulting from the frequent adjustment thereof with respect to the support to which attached.

It is therefore an object of my invention 35 to provide a simple efficient means for supporting curtains above the doors of an automobile or like vehicle so that the doors and the side curtains can be swung from open to 40 closed position or vice versa without the necessity of detaching any part of the side curtains from a support.

A further object of my invention is to 45 provide a device of the character described which is adapted to be operatively applied to automobiles having tops of conventional or ordinary construction without a change in the construction of the latter being required.

A still further object of my invention is 50 to provide an attachment of the character described which includes means for removably supporting a side curtain in a desired position in respect to a door of an automobile or other vehicle, whereby the curtain so supported can be detached from the ve-

hicle and folded in the usual manner for storage in a small space when not in use.

A still further object of my invention is to provide an attachment of the character described which includes means for normally holding a curtain supported thereon substantially in vertical alignment with a door with which associated when the latter is in closed position, and for yieldingly resisting movement of the curtain from closed to open position.

Other objects and advantages will be apparent from the following description, and the novel features of the invention will be particularly outlined in the appended claim.

My invention is illustrated in the accompanying drawing, forming a part of this application, in which

Figure 1 is a side elevation of an automobile body and top with portions broken away to show a practical embodiment of the invention operatively applied thereto.

Figure 2 is an enlarged perspective view of the attachment applied to the longitudinal bow of an automobile top.

Figure 3 is a view showing in elevation the outer face of a bracket included in the attachment.

Figure 4 is a side elevation of a flexible connector included in the attachment.

Figure 5 is a side elevation of a section of a curtain supporting member included in the attachment.

Figure 6 is a view similar to Figure 5 showing a second section of the curtain supporting member, and

Figure 7 is a side elevation of a retractile spring included in the attachment.

Referring now to the drawings, I show more or less diagrammatically the body 1 of an automobile of ordinary construction. A top 2, also of conventional or ordinary construction is provided for the automobile and includes side curtains 3 adapted to be arranged above the upper ends of doors 4 when the top 2 is operatively applied. The doors 4 are attached to the body by hinges, not shown, to swing outwardly from closed toward open positions, as is usual.

An attachment embodying the invention in the form now preferred by me, includes a bracket 5 comprising a vertical plate portion or arm 6 adapted to be attached by screws 7 or the like to the inner side of a longitudinal bow 8 of the top 2, or like support. The bracket 5 also includes a hori-

zontal plate portion 7 having on the upper face thereof an upstanding stud projection 10.

A sleeve 11 rotatably fitting the stud 10 and resting at one end upon the horizontal portion of the bracket 5 is formed integrally with a rod-like extension or shank 12 which extends at right angles to the axis of the sleeve 11 and is thus horizontally disposed when the sleeve 11 is mounted upon the stud 10 in the manner described. The shank 12 interfits the bore or an axial socket in a rod 13 which is of sufficient length to span the space above one of the doors 4 between the adjacent edges of the fixed side portions of the top 2, or in other words the length of the rod 13 is approximately the same as the width of one of the side curtains 3. A sleeve 14 is provided in the side curtain 3 along the upper edge thereof by means of stitching or the like and this sleeve is adapted to receive the rod 13, whereby the side curtains 3 will be swingingly supported for movement with the rod 13 about the axis of the vertical stud projection 10. The bracket 5 is attached to the bow 8 in position to substantially align the stud projection axially with the vertical axis about which the door 4 swings. When the side curtain 3 is attached at its lower end to the door 4 in any suitable known manner, as by means of buttons, the door and the side curtain will swing in unison from closed to open position, or vice versa.

The side curtain 3 is normally maintained in closed position, or in other words in edge-wise alinement with the door 4 when the latter is closed by means of a spring 15 of coil formation which is secured at one end by means of a screw 16 to the bow 8 at an appreciable distance from the bracket 5 and which is connected at its other end by means of a flexible connector 17 through a screw eye 18 extending from the juncture of the sleeve 11 and shank 12 at an angle to the shank 12. The arrangement is such that swinging movement of the shank 12 and of the rod 13 and the curtain supported thereon outwardly about the axis of the stud projection 10 is yieldingly resisted by the spring 15.

From the foregoing description of the various parts of the device, the operation thereof may be readily understood. An attachment is provided for each side curtain above each of the doors 4 and each door and the curtain associated therewith may be swung in unison from open to closed position or vice versa. The curtain is normally maintained in closed position by the action of the spring 15 as stated. When it is desired to remove the top 2 or the side curtains 3, the rod 13 is detached from the shank 12 and the side curtain 3 may be rolled thereabout so as to take up but little space. The bracket 5 may remain permanently attached to the bow 8 and the sleeve 11 and associated parts may be left in applied position when the side curtains 3 are not in use without detrimentally affecting the appearance of the top or in any way interfering with freedom of movement within the automobile.

Obviously, my invention is susceptible of embodiment in forms other than that illustrated in the accompanying drawings, and I therefore consider as my own all modifications of the form of the device herein disclosed, which fairly fall within the scope of the appended claim.

I claim:—

An attachment of the character described comprising a bracket having a vertical portion adapted for attachment to a fixed part of a vehicle top and a horizontal portion having an upstanding stud projection thereon, a sleeve rotatably mounted upon the upstanding projection and having a horizontal shank extending therefrom, a stiffening rod having a socket or bore adapted to slidably receive said shank, said rod being adapted to support a side curtain of a vehicle top at the upper end of the latter, and spring means arranged between the sleeve and the fixed part of the vehicle top for yieldingly resisting rotation of the sleeve in a direction outwardly from the body of the vehicle about the axis of the upstanding projection and for tending to cause rotation of the sleeve in a direction inwardly of the vehicle body.

EDWARD E. LAMICA.
